Primary Examiner — Karen E Kearney*Assistant Examiner* — Lilyana Bekic(74) *Attorney, Agent, or Firm* — Johnson | Dalal; Mark C. Johnson(57) **CLAIM**

The ornamental design for a mist spray, as shown and described.

DESCRIPTION

FIG. 1 is a perspective view of a mist spray in accordance with the present invention;

FIG. 2 is an elevational front view of the mist spray of FIG. 1;

FIG. 3 is an elevational rear view of the mist spray of FIG. 1;

FIG. 4 is an elevational left view of the mist spray of FIG. 1;

FIG. 5 is an elevational right view of the mist spray of FIG. 1;

FIG. 6 is a top plan view of the mist spray of FIG. 1; and, FIG. 7 is a bottom plan view of the mist spray of FIG. 1. The broken lines in the drawings depict portions of the mist spray device that form no part of the claimed design.

1 Claim, 3 Drawing Sheets(56)
